(57) **CLAIM**

The ornamental design for a hollow fiber element for filtration, as shown and described.

DESCRIPTION

FIG. 1 is a perspective view of a hollow fiber element for filtration showing my new design;

FIG. 2 is a front elevational view; the rear elevational view is the same as the front elevational view;

FIG. 3 is a right side elevational view thereof; the left side elevational view is the same as the right side elevational view;

FIG. 4 is a top plan view thereof;

FIG. 5 is a bottom plan view thereof;

FIG. 6 is an enlarged perspective view taken along line 6-6 and in the direction of arrows in FIG. 1;

FIG. 7 is an enlarged front elevational view taken along line 7-7 and in the direction of arrows in FIG. 2;

FIG. 8: is an enlarged front elevational view taken along line 8-8 and in the direction of arrows in FIG. 3;

FIG. 9: is an enlarged front elevational view taken along line 9-9 and in the direction of arrows in FIG. 4;

FIG. 10: is a cross-sectional view thereof taken in the direction of arrows 10-10 in FIG. 7; and,

FIG. 11: is a cross-sectional view thereof taken in the direction of arrows 11-11 in FIG. 7.
